Deal, N. J.

Application January 14, 1943, Serial No. 472,352

6 Claims. (Cl. 250—17)

(Granted under the act of March 3, 1883, as
amended April 30, 1928; 370 O. G. 757)

1

The invention described herein may be manufactured and used by or for the Government for governmental purposes, without the payment to us of any royalty thereon.

This invention relates to radio transmitters, particularly for pulse-echo work, and relates more especially to modulating means for such transmitters.

Systems for modulating a transmitter by means of a spark gap are already known, and the primary object of the present invention is to generally improve such systems.

Some prior spark gap modulating systems require auxiliary control electrodes or other means to start the spark. Some require an air-blast or other means to quench or stop the spark. Some employ rotating electrodes with appropriate driving gear. One of the main objects of our invention is to dispense with the need for any of the aforesaid auxiliary means, with their attendant disadvantages.

In terms of practical apparatus, power for the spark gap modulator may be obtained from a low-voltage A.-C. source by using a step-up transformer and a rectifier. Such a source usually needs filter elements, and these are bulky and expensive when large power is to be handled. Another more specific object of our invention is to devise a modulator adapted to operate from such a power source having poor filtration or low capacitance. In fact, one efficient form of our apparatus may be said to operate better with low capacitance and poor filtration than with good filtration.

Another object of our invention is to provide a spark gap modulator which will generate pulses of extremely high voltage and amperage while using equipment which is compact, simple, inexpensive, and dependable. Other objects of our invention are to provide a spark gap modulator which is characterized by long life, which is devoid of moving parts, and which requires the use of only two low-power rectifier tubes, thereby conserving on tubes. Another object is to provide a spark gap modulator which is insensitive to wide changes of temperature, thus making it suitable for use in either polar or equatorial regions.

Still further objects are to provide a spark gap modulator capable of generating pulses which may be varied in width to provide either a very narrow or a very wide pulse as desired, and which may be varied in frequency over a very wide range of say two or three to one by simple turning a knob. The ability to readily change the keying rate helps avoid intentional interference by some-

2

one who may have gained knowledge of the keying rate previously used. Along this line, still another object is to provide a pulse generator or modulator which is relatively non-periodic. This is no advantage with modern pulse-echo systems in which the receiver oscilloscope may be triggered by the transmitter pulse yet it is of advantage in making it more difficult to interfere with the transmitter pulses.

10 To accomplish the foregoing and other objects which will hereinafter appear, our invention resides in the spark gap modulator elements and their relation to one another and to the transmitter, as hereinafter are more particularly described in the specification and sought to be defined in the claims. The specification is accompanied by drawings in which

Figure 1 is a side elevation of a spark gap modulator embodying features of our invention;

20 Figure 2 is a schematic wiring diagram of a transmitter including the spark gap modulator shown in Figure 1;

Figure 3 illustrates a detail of a section of the cathode and is taken approximately in the plane of the line 3—3 of Figure 1;

Figure 4 illustrates a detail of the anode and is taken approximately in the plane of the line 4—4 of Figure 1;

Figure 5 is a plan view of the spark gap mechanism;

Figure 6 is a section taken approximately in the plane of the line 6—6 of Figure 5;

Figure 7 is a vertical elevation taken approximately in the plane of the line 7—7 of Figure 5;

35 Figure 8 is a bottom view of the spark gap modulator shown in Figure 1; and

Figure 9 is a plan view of a detailed portion of Figure 5, drawn to enlarged scale in order to clarify the construction.

40 Referring to the drawing and more particularly to Figure 2, the transmitter comprises a D.-C. source generally designated S, and an ultra-high-frequency transmitter generally designated T. The transmitter is keyed by high-power pulses generated in a spark gap modulator generally designated K. This consists of a network of series-connected inductors and shunt-connected condensers with spark gaps connected diagonally therebetween as shown. The arrangement is such that the condensers are charged in parallel, but are discharged in series, so that the resulting pulse has the cumulative potential of all of the condensers. The network K is connected to the D.-C. source S through an impedance Z, said impedance functioning to isolate

50 55

the source S from the network K when the gaps break down. In this way a single pulse is obtained. Another network W may be inserted between the network K and the transmitter T in order to better shape or "square" the pulse.

The pulse voltage which may be generated in this fashion is so high that it may be used directly as a polarizing potential for the transmitter tube, that is, a positive pulse may be applied directly to the anode of the tube. In the specific circuit which we have illustrated, the tube is operated in inverted fashion, the anode being grounded, and a negative pulse being applied to the cathode of the tube. With either arrangement the tube will oscillate only intermittently, and only while polarized by the pulse potential.

The impedance Z is important in order to prevent a continuous arc or spark which might draw hundreds of amperes. This impedance is made sufficiently high so that the condensers cannot recharge fast enough to support the arc, and the spark is therefore immediately extinguished. When once extinguished the spark will not strike again until the condensers build up the necessary high voltage.

Although we have referred to the source S as a D.-C. source, the modulator is more directly operable from an ordinary 60-cycle A.-C. line, the source S then consisting simply of a voltage-varying means, a step-up transformer, and a rectifier. In the present case, the voltage-varying means is an autotransformer 10. The transformer consists of a primary 12, and a secondary 14, the output of which is supplied to diodes 16 and 18. These are faced in opposite directions, and in proper direction to obtain either a positive or negative pulse, as desired. Condensers 20 and 22 are connected in series between the impedance Z and ground as shown, so that the circuit constitutes an elemental form of voltage doubler. No special elaborate filter is provided to smooth the D.-C. output and, in fact, a source of low capacitance is preferable when using an inductive impedance 30, as shown. The inductive impedance is preferable because it is more efficient in avoiding the heat dissipation which accompanies the use of a resistive impedance. With a resistive impedance, however, the D.-C. source may be a source having a smooth output potential.

The operation of the network K will be clear on a moment's reflection, for the charging of the condensers takes place relatively slowly and is not obstructed by the chokes 16, 18, hence the condensers 14 are all charged in parallel. However, when the charge on the condensers reaches a potential sufficient to break down the gaps, the discharge is a very abrupt surge of current which is blocked by the chokes but which can readily flow from the first condenser through the first gap, to the second condenser and thence through the second gap, to the third condenser, etc., without flowing through the chokes at all. This results in a discharge through all of the condensers and gaps in series, so that the pulse potential is equal to the sum of the individual condenser potentials. In a typical case the breakdown voltage for each section of the network, that is, for each condenser and gap, may be say 5,000 volts, in which case the output pulse when using say eight gaps, as here illustrated, will be about 40,000 volts.

In respect to the operation of the circuit, it may be explained that the inductance of the chokes

in network K is negligible compared to the far greater inductance of the impedance Z. During charging of the condensers the circuit may be considered as comprising only the source S, the impedance Z, and the storage condensers 14 connected in parallel at the output of the impedance Z. During discharge of the condensers 14, the circuit may be considered as consisting only of the network K in series with the waveshaper W, for the impedance Z in effect separates the network K from source S. The time required to charge the condensers to maximum potential value before breakdown of the spark gaps must be larger than the lowest period at which the system is likely to be operated.

When using an inductive impedance, the impedance Z itself acts as a voltage doubler. The flow of current from source S will tend to produce oscillations, for the initial potential rise is carried on by the inertia of the inductor Z to a value nearly twice as high as that of the source. In the absence of the spark gaps this would be followed by a voltage drop which overshoots, then another voltage rise which overshoots, and so on, resulting in a damped train of oscillations which would finally settle down to a steady state voltage equal to the voltage of the source S. However, the spark gaps are adjusted to break down at a voltage somewhat below the peak voltage of the first upward swing. The resulting spark is a short circuit which pulls the voltage down to zero and thus abruptly arrests the incipient train of oscillations, whereupon the condensers begin to be charged from zero, and the charge again rises to nearly double voltage because of the action of the inductor Z.

The wave-shaper W may take any of a considerable number of forms. A typical wave-shaper is one of the Guilleman type lines. The network shown here is far simpler but is adequate for the present purpose. It comprises an inductor 30 in series with a parallel resonant circuit made up of a capacitor 32 and an inductor 34.

The Guilleman type line would be similar to the network W but would have three more parallel resonant circuits following that shown. The simplified network W here shown is employed merely to reduce the amount of apparatus required, for we have found that by empirically setting the value of the capacitor 32 and the inductor 34 the succeeding three parallel resonant circuits may be eliminated. The resulting pulse wave does not have as good a square shape as would be obtained when using the complete Guilleman type line, but is good enough for the present purpose.

The particular transmitter here shown is intended to operate at a frequency of about 600 mc. and employs a so-called "Vt-158" tube, which is described in detail in copending applications of Harold A. Zahl, Serial No. 473,556, filed January 25, 1943, entitled, "Electronic tube," and Harold A. Zahl, Glenn F. Rouse, and John E. Gorham, Serial No. 496,654, filed July 29, 1943, now Patent No. 2,454,298 issued November 23, 1948, entitled "Electronic tube." The said tube consists of two sets of triode electrodes, arranged in push-pull, with grid-to-grid and anode-to-anode loops all disposed within a vacuum tube envelope. In Figure 2 the anodes 36 and 38 are connected by an anode loop 40, and the grids 42 and 44 are connected by a grid loop 46. Grid bias may be applied at 48. The heating circuits for the cathodes have been omitted. The cathodes are tuned by means of an external loop 50, adjusted by a short-

ing bar 52. The anodes are also tuned by an external loop 54, adjusted by a shorting bar 56. Power is taken from the loop 54 over any desired form of transmission line, but in the present case, for purposes of simplification, power is assumed radiated directly from a dipole antenna 58.

To modulate the transmitter, the cathodes may be grounded at 60 and a positive pulse from the modulator may be applied to the anode at 62. However, in the specific case here illustrated, the anodes are grounded at 62 and a negative pulse from network K and wave-shaper W is applied to the cathodes at 60. The rectifiers 16 and 18 are properly poled to provide the necessary negative pulse.

It will be understood that although a particular transmitter and oscillator tube have been mentioned, our modulator system may be used with other transmitters and tubes.

Other features of the invention will be understood by reference to the structural arrangement of the parts of the network K. Referring to Figure 1, a chassis plate 64 is secured to a front panel 66. A row of spark gaps 68 (Figures 1 and 5) is disposed above the chassis plate 64. Each spark gap comprises a cathode 70 and an anode 72. The electrodes are relatively movable to adjust the gap therebetween, this preferably being conveniently and accurately done by means of a control handle H (Figure 1) at the front of the panel. The gap adjustment may be used to control the output voltage, for the breakdown voltage depends on the length of the gap. Also, for any given gap length the control handle H may be used to compensate for dissipation or wear of the electrodes. This wear is very slight and unnoticeable, being only a matter of say 0.001 inch per day, so that a set of electrodes will last for years. In practice the operator will ordinarily tune the transmitter once a day or once every few days, and while doing so will vary the control knob H for proper adjustment of the modulating voltage, and this will make up for any preceding wear of the electrodes.

A row of condensers 74 (Figures 1 and 8) is mounted beneath the chassis plate 64, and rows of chokes 76 and 78 are mounted at each side of the condensers 74. By properly locating the chokes and condensers along the bottom of the chassis beneath the spark gaps at the top of the chassis, these parts may be connected by short direct vertical leads (not shown). At the same time, the spark gaps are disposed at the top for easy observation and adjustment. A row of series-connected chokes 80 may also be disposed along the bottom of chassis 64, all of these chokes making up the single impedance Z previously referred to.

Considering the spark gap structure in greater detail, the cathodes 70 and the anodes 72 rest on V-grooved brass blocks 84 and 86, as is best shown in Figures 3 and 4. The electrodes are rods of a suitable high-temperature metal, for example tungsten or molybdenum, and are held in position by appropriate flat springs 88 and 90, the outer ends of said springs being secured to the outer ends of the blocks by screws 92 (Figures 1, 5, and 7). Blocks 84 are secured in spaced parallel relation on an insulation strip 94, and blocks 86 are secured to another insulation strip 96. The insulation for strips 94 and 96, and also the chassis plate 64, may be a material known commercially as "Mycalex." Strip 94 is mounted on two preferably insulation posts 98 (Figure 1), the upper ends being held by screws 100 (see

Figure 5) and the lower ends being similarly secured to a base plate 102. In the present case, plate 102 is stationarily mounted on the chassis plate by means of four stand-off insulators 104, two of which are visible in Figure 1.

The insulation strip 96 is similarly mounted at the upper end of two stand-off insulators 106 (Figures 1 and 7), as by means of screws 108 (Figure 5). The lower ends of posts 106 are carried by a cross bar 110 (Figures 1, 6, and 7), which is either formed integrally with or is rigidly secured to a slide 112 (Figure 6). Slide 112 is dovetail-shaped in section, and is guided between bottom plate 102 and guide plates 114, which may be adjustably secured on plate 102, to guide the slide 112 with a close fit.

Referring now to Figures 1, 5, and 9, the knob or handle H is secured at the outer end of a rotatable shaft 116. This passes through a stationary bearing block 118 mounted at the forward end of base plate 102. Collars 120 are secured to shaft 116 at opposite sides of bearing 118, thereby holding the shaft against axial movement. The inner end of shaft 116 is threaded, preferably with a very fine, accurately-tooled thread. This is received in a mating female thread, formed in the slide 112 previously referred to. It will be evident that by rotating the shaft 116, the slide 112 will be moved either forward or backward, thereby varying the spacing between the stationary and movable electrodes of the entire row of spark gaps.

In order to eliminate slack or lost motion, which might interfere with accurate control at the handle H, we employ compression springs 124, which are disposed between the stationary bearing 118 and the forward end of the movable slide 112. These compression springs take up "play" or slack in the shaft bearing and in the thread while the shaft is being turned in either direction. As a further precaution, and in order to introduce a desired amount of friction against rotation of the shaft, a plate 126 is secured in front of the slide 112, said plate being slotted at 128 (Figure 7) and provided with a clamp screw 130. Plate 126 is threaded to mate with the threaded shaft 116, and by tightening the clamp screw 130 the slotted thread may be tightened around the shaft to introduce any desired degree of friction.

The compression springs 124 are preferably carried by rods 132 (Figure 9) which are secured at one end and are slidable at the other. In the present case, the forward ends 134 are slidable through the bearing 118. The inner ends 136 are threadedly received in slide 112. Integrally formed collars 138 are provided, which act as bolt-heads bearing against the plate 126 and securing the same to the forward end of slide 112. Thus, the rods 132 act not only as supports and guides for the compression springs, but also as bolts to hold the friction plate 126 on the forward end of slide 112.

As is known, the cathode of a spark gap is volatilized or sputtered away far more rapidly than the anode, the wear of the anode being negligible compared to that of the cathode. In the present structure, the cathodes 70 are of relatively small diameter. We prefer a small-diameter rod to a large-diameter rod because we have found that with a large-diameter rod a crater is formed at the center which makes it difficult to readjust the electrodes to make up for wear. If, on the other hand, a small-diameter rod is employed, it is eaten away entirely across its end surface, thus

presenting a generally flat working end to the anode. As the cathodes are worn away, the wear may be made up by readjustment at the handle H. After a substantial amount of wear, say a fifth-inch, corresponding to say a half-year's use, the handle H may be rotated in the opposite direction to back the anodes far away from the cathodes, whereupon the cathode rods may be slid out by hand until they touch or nearly touch the anodes. By advancing the anodes, the cathodes will automatically be aligned, and by then backing away the anodes, a uniform gap space will be provided at all of the spark gaps. This same mechanism facilitates replacement of the cathodes, but the wear is very gradual, and a single set of electrodes operating continuously day and night will last for years.

The anodes 72 may be made of larger diameter, and it is ordinarily unnecessary to advance or to replace the same, hence they may be made relatively short. The anodes preferably bear against positive stops in order to fix the same in position, whereas the cathodes are held solely by the pressure of the springs 88. In Figure 5 the springs of the right-hand spark gap have been broken away, and it will be seen that the V-grooved block 86 is provided with a stop screw at 140 abutting the end of anode 72.

The storage condensers are cylindrical in form and are bolted at their upper ends to the chassis plate 64. Figure 1 shows one of the condensers 74 held by a screw 142, while Figure 8 shows the entire line of condensers. It will be understood that connection to the terminals of the condensers is made at the upper and lower ends, the lower connection being indicated by an appropriate soldering lug 144 (Figure 1).

The chokes 76 and 78 are supported on horizontal rods of insulation 146 (Figures 1 and 8) which, in turn, are mounted on vertical insulation posts 148 (Figure 1). Each of the chokes 76 shown in Figure 2 is structurally wound as two pancake-shaped coils, preferably with a honeycomb winding. These two coils are connected in series. Each pair of coils is received on one of the horizontal rods 146. These rods may be cut away to overlap at their ends, the overlapping ends being screwed to the posts 148. The screws for this purpose are indicated at 150 in Figure 8.

In the particular case here illustrated, the impedance Z is an inductive impedance and is made up of four iron-cored inductors disposed side by side, as indicated at 80 in Figure 8. If desired, these may be suspended from upright insulators 152 (Figure 1), which, in turn, are secured to the chassis plate 64.

While the invention is applicable to a variety of conditions as to pulse frequency and power, etc., an illustrative example of some of the quantitative dimensions which we employed in one particular spark gap modulator are given hereinafter. For a pulse frequency of say 250 cycles and a potential of about 20,000 volts and pulse width of about 1 microsecond, we used chokes 76 and 78 having an inductance of about 75 millihenries. The storage condensers 74 had a capacitance of 0.01 microfarad. The impedance Z totalled 48 henries. The network was supplied with power from an ordinary 110-volt, 60 cycle source, which was fed through a "Variac" auto-transformer (0 to 110 volts) to a step-up transformer, the secondary of which delivered a voltage of about 1500 volts. This was doubled by the voltage-doubling action of the rectifier to a peak voltage of about 3000 volts. This, in turn, was

again doubled by the impedance Z to a peak value of about 6000 volts. The storage condensers tend to charge up to that voltage, but the gaps were set to break down at say 5000 volts. With 8 gaps the voltage was 40,000, of which about half was lost in the wave-shaper.

The rectifier tubes 16 and 18 were ordinary tubes of the type 366A, and the series capacitors 20 and 22 each had a value of 1.0 microfarad.

The spark gaps employed cathodes made of tungsten rods having a diameter of $\frac{1}{2}$ of an inch, and a length of say 1 $\frac{1}{2}$ inches, though even a length of $\frac{3}{4}$ inch is adequate for long life. The anodes were made of tungsten rods having a diameter of about $\frac{1}{4}$ inch.

The wave-shaping circuit shown in Figure 2 used an inductor 30 having a value of about 120 microhenries, a capacitor 32 having a value of about 0.0006 microfarad, and an inductor 34 having a value of about 40 microhenries.

It will be understood that the foregoing quantitative dimensions have been given solely by way of illustration and not in limitation of the invention. The dimensions will vary widely with changes in pulse power, pulse voltage, pulse frequency, etc. Moreover, if a resistive impedance is used instead of an inductive impedance, the smoothing condensers 20 and 22 may be much larger in magnitude. The use of a resistive impedance reduces the efficiency somewhat because of heat dissipation in the resistor, but, even so, the system is a highly efficient one compared to other keying systems. When using the more efficient inductive impedance, it is desirable not to use unnecessarily large condensers at 20 and 22, because if made too large, the spark will tend to persist.

It is believed that the construction and operation of our improved spark gap keyer will be understood from the foregoing detailed description. The storage condensers are charged until the potential thereon equals the critical value for breakdown of the spark gaps, whereupon the gaps conduct. Although the condensers are charged in parallel because the chokes 76 and 78 do not appreciably impede the relatively slow charging current, the condensers are discharged in series because the chokes effectively block the sudden pulse delivered when the gaps break down. The sparks are quenched when the potential on the condensers falls to a value below that needed to maintain the spark, and this takes place very quickly, in fact, almost instantly, because the high impedance Z prevents rapid recharging of the condensers. Because the pulse potential is the cumulative potential of all of the condensers, the pulse obtained is a very powerful one, yet it is so rapidly quenched that a pulse of only a few microseconds duration may be obtained if desired.

The frequency of the pulse depends on the values of the impedance Z, the storage condensers, the D.-C. input voltage from the source S, and the gap spacing. An increase in gap spacing results in an increase in potential up to the limit of the available charging potential. The duration of the pulse is a function of the load, and of the size of the storage condensers, as well as the shaping circuit W. The pulse frequency varies with the input voltage for a constant gap spacing. The pulse voltage varies with the gap spacing, but a change in gap spacing will incidentally vary the pulse frequency somewhat. If one wishes to change the pulse frequency while maintaining the pulse voltage, the input voltage should be changed by moving the control knob of

the "Variac" autotransformer 10. If one wishes to change the pulse voltage while maintaining the pulse frequency, it is necessary to change the gap spacing, and to then somewhat change the input voltage in order to compensate for any change in pulse frequency which may arise as an incident to the change in gap spacing. The ease with which the pulse frequency may be changed is of considerable benefit in the field, in order to overcome attempted enemy interference with the 10 transmission.

Many of the advantages of the present transmitter and keyer will be recognized from the foregoing description, but by way of summary, it may be pointed out that the keyer is compact, simple, light, devoid of moving parts, and employs only two low-power rectifier tubes, yet is capable of delivering extraordinary high power output. The structure conserves on tubes. It is rugged, and is insensitive to wide temperature variation, so that it may be satisfactorily used in arctic or desert regions. The keyer does not require an air blast to quench the spark, nor an auxiliary electrode or auxiliary pulse circuit to start the spark. The keyer may be designed to produce a narrow or a wide pulse, as required, and the pulse frequency may be varied over a wide range of say, 2 or 3 to 1, by simply turning a knob to change the input voltage. Because the pulse is not strictly periodic, it is more difficult for a hostile transmitter to interfere with the present transmitter. There is also the advantage that pulses from other nearby friendly pulse-echo systems will not interfere with effective reception from the present system, because the neighboring systems will have either a periodic pulse, or a non-periodic pulse randomly different from the present non-periodic pulse.

It will be apparent that while we have shown and described our invention in a preferred form, many changes may be made in the structure disclosed, without departing from the spirit of the invention as sought to be defined in the following claims.

We claim:

1. Apparatus for modulating a transmitter, said apparatus comprising a potential source, an inductive impedance, a network having a plurality of condensers, chokes connecting said condensers in parallel, and spark gaps connecting said condensers in series, means for applying said potential source in series with said impedance to said network, whereby said condensers charge in parallel until the voltage thereon equals the breakdown voltage of said spark gaps, whereupon said condensers discharge in series so that the resulting pulse has the cumulative potential of said condensers, said impedance in combination with said parallel condensers forming an oscillatory circuit and serving to increase the charging voltage on said condensers, said impedance also functioning to impede the charging current to quickly quench the spark, and means to feed said pulse to the transmitter to modulate same.

2. Apparatus for modulating a transmitter tube, said apparatus comprising a D.-C. potential source, means to vary the output potential of said source, an inductive impedance, a network having a plurality of condensers, chokes connecting said condensers in parallel, and spark gaps connecting said condensers in series, means for applying said potential source in series with said impedance to said network whereby said condensers charge in parallel until the voltage thereon equals the breakdown voltage of said spark gaps, whereupon

said condensers discharge in series so that the resulting pulse has the cumulative potential of said condensers, said impedance in combination with said parallel condensers forming an oscillatory circuit and serving to increase the charging voltage on said condensers, said impedance also functioning to impede the charging current to quickly quench the spark, and means to feed said pulse to an electrode of the transmitter tube in order to drive the tube.

3. Apparatus for modulating a transmitter tube, said apparatus comprising a D.-C. potential source, an inductive impedance, a network having a plurality of condensers, chokes connecting said condensers in parallel, and spark gaps connecting said condensers in series, means for applying said potential source in series with said impedance to said network whereby said condensers charge in parallel until the voltage thereon equal the breakdown voltage of said spark gaps, whereupon said condensers discharge in series so that the resulting pulse has the cumulative potential of said condensers, said impedance in combination with said parallel condensers forming an oscillatory circuit and serving to increase the charging voltage on said condensers, said impedance also functioning to impede the charging current to quickly quench the spark, a wave-shaping network in the discharge path of said condensers to square the wave-form of the resulting pulse, and means to feed said pulse to an electrode of the transmitter tube in order to drive the tube.

4. A transmitter for pulse-echo work, said transmitter comprising a D.-C. potential source 35 having minimum size smoothing capacitors, a large inductive impedance, a network having a plurality of condensers, chokes connecting said condensers in parallel, and spark gaps connecting said condensers in series, means for applying said potential source in series with said impedance to said network whereby said condensers charge in parallel until the voltage thereon equals the breakdown voltage of said spark gaps, whereupon said condensers discharge in series so that the resulting pulse has the cumulative potential of said condensers, said impedance in combination with said parallel condensers forming an oscillatory circuit and serving to increase the charging voltage on said condensers, said impedance also functioning to impede the charging current to quickly quench the spark, a wave-shaping network in the discharge path of said condensers to square the wave-form of the resulting pulse, and a transmitter tube having a tank circuit associated therewith, the output from the wave-shaping network being applied to the transmitter tube to act as the D.-C. driving potential for the same.

5. Apparatus for modulating a transmitter, said apparatus comprising a D.-C. potential source including a low voltage A.-C. supply, a step-up transformer for said supply, a rectifier and filter capacitors, said capacitors being of minimum size for poor filtration, an inductive impedance, a network having a plurality of condensers, chokes connecting said condensers in parallel, and spark gaps connecting said condensers in series, means for applying said potential source in series with said impedance to said network, whereby said condensers charge in parallel until the voltage thereon equals the breakdown voltage of said spark gaps, whereupon said condensers discharge in series so that the resulting pulse has the cumulative potential of said condensers, said impedance in combination with said parallel condensers forming an oscillatory circuit and serving

to increase the charging voltage on said condensers, said impedance also functioning to impede the charging current to quickly quench the spark, a wave-shaping network in the discharge path of said condensers to square the wave-form of the resulting pulse, and means to feed said pulse to the transmitter tube in order to modulate same.

6. Apparatus for modulating a transmitter tube, said apparatus comprising a D.-C. potential source, means to vary the output potential of said source, an inductive impedance, a network having a plurality of condensers, chokes connecting said condensers in parallel, and spark gaps connecting said condensers in series, said spark gaps being disposed in spaced collateral relationship, the cathodes of said spark gaps being relatively long, small-diameter rods of high-temperature metal, the anodes of said spark gaps being relatively short, large-diameter rods of high-temperature metal, said cathodes being carried by a first insulation strip and projecting transversely from one edge of said strip, said anodes being carried by a second insulation strip and projecting transversely from one edge of said second strip, said strips being mounted for adjustment toward or away from one another in order to change the gap spacing between the cathodes and anodes, the cathode rods being slidably held by friction springs in order to be axially movable to make up for wear of the said rods, means for applying said potential source in series with said impedance to said network whereby said condensers charge in parallel until the voltage thereon equals the breakdown voltage of said spark gaps, whereupon said condensers discharge in series so that the resulting pulse has the cumulative potential of said condensers and means to

feed said pulse to the transmitter to modulate same.
